UNITED STATES PATENT OFFICE.

HUGH PERRONET THOMPSON AND LOUIS MONTÉ, OF CHICAGO, ILLINOIS,
ASSIGNORS TO THE SHONE COMPANY, OF SAME PLACE.

MEANS FOR STARTING AND REGULATING OIL OR GAS ENGINES.

SPECIFICATION forming part of Letters Patent No. 626,252, dated June 6, 1899.

Application filed August 26, 1897. Renewed April 6, 1899. Serial No. 711,894. (No model.)

To all whom it may concern:

Be it known that we, HUGH PERRONET THOMPSON and LOUIS MONTÉ, of Chicago, in the county of Cook and State of Illinois, have 5 invented certain new and useful Improvements in Means for Starting and Regulating Oil or Gas Engines, of which the following is a full, clear, and exact description, reference being had to the accompanying drawings, forming a part of this specification, in 10 which corresponding letters of reference in the different figures indicate like parts.

Our invention relates to oil, naphtha, and 15 gas engines or engines in which a charge of explosive material is ignited to produce the required power; and the object of our invention is to provide simple automatic mechanism whereby the tendency to variations of speed due to fluctuations of load or other 20 causes usually met with during the operation of an engine may be approximately corrected and a sufficient number of the explosive charges cut out or supplied to cause the engine to reassume its normal speed and in the 25 event of a very great reduction in speed or the failure of the governor to act as a result of the breaking or slipping of the belt that the charges may be cut out and the engine caused to stop.

30 A further object is to provide means whereby a single operator may be enabled to actuate the engine in starting and so control it that either no charges at all may be drawn or that the engine may be made to draw continuous explosive charges until the normal 35 speed is attained. Moreover, it is our purpose to so construct said controlling mechanism that it may act automatically in conjunction with the usual governor or without it— 40 that is to say, that in starting the engine the normal action of the governor may be arbitrarily modified by the operator and temporarily suspended, and in case the governor-belt should break the explosive charges may 45 be automatically cut out and the engine prevented from "running away," all of which is hereinafter more particularly described, and definitely pointed out in the claims.

50 In the drawings, Figure 1 is a plan view, partly in section, of an engine embodying the features of our invention. Fig. 2 is an en-

larged plan view, partly in section, of that portion of an oil-engine to which our improvements are attached and showing said improvements. Fig. 3 is a side elevation thereof. 55 Fig. 4 is a view showing a rear elevation of said engine, and Fig. 5 shows a modified form of regulator.

Referring to the drawings, *a* represents the frame of an ordinary engine, upon which is 60 mounted the usual cylinder *b*, with piston *c*, piston-rod *d*, and crank-shaft *e*. Within a casing connected directly with the forward end of the cylinder is a chamber *f*, Figs. 1 and 2, which is in communication with said cylinder and also, through a port *g*, Fig. 2, with the atmosphere and also with an oil-reservoir *h*, Fig. 4. A valve (not shown) opening inwardly permits the oil and air to flow into the chamber *f*, but is closed upon compression of 65 the explosive charge, as hereinafter stated. The chamber *f* is also in communication with the usual exhaust-pipe *i*, Figs. 2, 3, and 4, between which and said chamber is interposed an exhaust-valve *j*, mounted upon a valve- 70 stem *k*, Figs. 1, 2, and 4. The chamber *f* is also in communication through the port *g* with an ignition-tube *l*, Fig. 4, which is kept hot by means of an oil-lamp *m* in the usual way. 75

Pivotedly connected with the valve-stem *k* 80 is a lever *n*, which is pivoted, as shown, to a bracket *o*, extending from the frame. A pitman *p* in operative connection with an eccentric upon or connected with the engine-shaft is pivotally attached to a rod *q*, adapted to engage the lever *n*, or preferably an adjusting-screw thereon, as shown, with each revolution of the eccentric and by its backward movement to open the valve *j* during the backward movement of the piston *c*, thereby 85 permitting the escape of the exploded charge to the open air. The valve *j* is held normally closed by means of a spiral spring *r*. 90

Pivotedly secured to a bracket *s* is a lever *t*, one end of which is connected by means of 95 a yoke to the usual sleeve *t'* of a governor mechanism, while the other is pivotally attached to a sliding bar *u*, arranged to slide vertically in a suitable bearing. Upon the lower end of the bar *u* are formed lugs *v w*, 100 (better shown in Figs. 2 and 3,) which are severally adapted, when in alignment therewith,

to engage a lug x upon the outer end of the lever n .

Pivoted to the bracket s is a lever y , Fig. 3, one end of which is arranged to bear beneath the short end of the lever t , while the other end is connected by means of a chain y' to a treadle z , so arranged that when the latter is pressed downwardly the short end of the lever y is raised with it, (the short end of the lever t ,) together with the sleeve t' , so as to cause the notch or space between the lugs $v w$ to be brought into alinement with the lug x , provided always that at the time of depressing the treadle the speed of the engine is not so great as to have already lifted the lever t clear of the lever y .

The governor is driven in the usual way by means of a belt t^2 , Fig. 1.

Having thus described the various parts of our improved device, we will now explain its operation.

The lugs $v w$ are so adjusted upon the bar u that the notch or space between them is considerably wider than the lug x . They are also so adjusted upon the bar u with reference to the vertically-movable sleeve t in the following manner: When the engine is running at normal speed, so as to maintain the sleeve t' in a given position vertically, the lug x will enter the space between the lugs $v w$ immediately underneath the lug v and well clear of the lug w with each revolution of the eccentric, and thus permit the valve j to close regularly. In case the speed increases so as to cause the sleeve t' to rise slightly the lug v is brought into opposition to the lug x , and so prevents the valve j from closing until the engine reassumes its normal speed. When the sleeve t' is at the lower end of its travel, either on account of the engine being at rest or its speed being sufficiently reduced or through the governor-belt breaking, the bar u is raised high enough to bring the lug w into opposition with the lug x and so prevent the valve j from closing in the same manner as described in relation to the lug v , except that in the latter case the lug w cannot again clear the lug x automatically. The normal speed of the engine when working under its normal load should be taken into account in adjusting the lugs $v w$ with respect to the lug x , and this adjustment should be such that the tendency of the engine will be to increase its speed under normal load and continuous discharges. Hence we have found in practice that the most satisfactory results are attained when said parts are so adjusted with respect to each other as to cause about one charge in ten to be cut out when the engine is running at full power. This factor or tendency toward an increase of speed we have found to be sufficient to take care of all ordinary variations of load and to prevent the engine from stopping except upon the failure of the governor to act as a result of the breaking of the belt or other similar cause, when the lug w is immediately brought into action. It should be borne in

mind that by reason of the described adjustment of the parts so as to cause a tendency toward an acceleration of speed the lug v is always brought into and out of action automatically, while, on the other hand, the lug w after having once engaged the lug x cannot again be brought into action automatically. The action of the parts described with reference to the explosion is as follows: With the forward stroke of the piston a charge of air and oil is drawn into the chamber f through the port g . Upon the completion of the forward stroke the puppet-valve controlling the charge, which valve is not shown, is automatically closed, and the charge is compressed as a result of the return stroke, thereby forcing a portion of the charge into the ignition-chamber, when at the time of greatest compression an explosion occurs which serves to drive the piston forward. At the end of the forward stroke the exhaust-valve j is opened inwardly by means of the lever n , rod q , and pitman p . The opening of the exhaust-valve permits the products of combustion from the exploded charge to escape to the atmosphere, and the piston upon the return stroke drives out the greater part of the remainder. When the piston reaches its extreme backward movement, the exhaust-valve j is closed and so retained by means of the spring r . This completes the cycle of operations, and the piston upon the next forward stroke draws in a fresh supply of oil and air. Should the engine exceed its normal speed, the governor-sleeve rises, the slide-bar u is depressed, and when the exhaust-valve is opened the lugs $x v$ are brought into engagement, which blocks the lever n against the action of the spring r and holds the exhaust-valve open. As a result the next forward stroke of the piston merely draws back the exploded charge and expels it again with the backward stroke instead of drawing in and compressing a fresh charge. This operation is repeated until the speed of the engine diminishes sufficiently to raise the lug v clear of the lug x , when the engine receives a fresh charge. Thus it will be seen that as long as oil and air are supplied to the engine it will continue to run at its normal speed, provided always that a continuous series of charges are sufficient to drive it at or above this speed.

Should the governor-belt break or slip off, the governor stops and the sleeve t' moves to the lower end of its travel and raises the part u so high that the lug w is brought into engagement with the lug x , thereby holding the exhaust-valve open in the same manner as was done by the lug v . The engine therefore stops for want of a fresh charge.

Upon shutting off the supply of oil the engine continues to run with its own momentum, the speed gradually decreasing, the valve j closing, and the engine drawing in and compressing regularly non-explosive charges of air only until the speed has become reduced to such an extent that the governor-sleeve t'

reaches the lower end of its travel, whereupon the lug *w* is raised into opposition with the lug *x*, the exhaust-valve *j* is held open, and the engine continues to revolve, merely drawing in and expelling air through the open exhaust-valve until it comes to rest. The exhaust-valve remains open thus until it is required to restart the engine.

Our improved device described in connection with the lever *y* and chain and treadle enables the engine to be readily started by a single operator. The starting is accomplished by opening the oil-valve, turning the balance-wheel by hand until more or less momentum is obtained, (the piston meanwhile merely drawing in and expelling air through the open exhaust-valve,) and pressing the foot-lever so as to cause the lever *y* to raise the governor until the lug *x* is brought into alignment with the space between the lugs *v* *w* or in the position assumed by the respective parts when the engine is running at normal speed. The exhaust-valve being free to close, the engine at once begins to take and explode charges. The treadle should be kept depressed until the engine equals or exceeds its normal speed, this latter condition being indicated by the lug *v* coming into operation automatically and cutting out some charges. The sleeve *t* of the governor is then so high that it will have lifted the lever *t* altogether clear of the lever *y*, the lug *w* being in consequence still farther removed from opposition with the lug *x* than had been accomplished by means of the treadle. There is then no danger of the lug *w* coming into operation, except under the circumstances for which it is designed, and which the release of the treadle will leave it free to do, and the engine will proceed to govern itself automatically during the usual course of running by means of the lugs *x* and *v* only.

In order that the operation of the engine may not be misunderstood, we desire to again state that the lug *w* engages normally with the lug *x* whenever the speed of the engine is impeded as a result of cutting off the oil-supply. These two lugs then remain in opposition and hold the exhaust-valve open until the foot-lever is depressed upon restarting the engine. It should be borne in mind that the depression of the treadle cannot and is not intended to interfere with the automatic governing of the speed of the engine above the normal, hence the object in depressing the treadle until the normal speed is exceeded. When the normal speed shall have been exceeded, the treadle may be released, as there is then no danger of the lug *w* coming into action unless required, which the release of the treadle leaves it free to do.

In order to allow for a moderate variation in the speed of the engine—such, for example, as the reduction of speed resulting from a sudden additional load—it is desirable that the space between the lugs *v* *w* should be sufficient to permit a slight play between them

and the part *x*. Otherwise the device might serve to defeat the purpose intended. A very slight play, however, not to exceed three ⁷⁰ thirty-seconds of an inch, is ample.

While we have described our improvement in connection with an oil-engine, it is obvious that it is applicable to any similar form of naphtha or gas engine and that the means ⁷⁵ employed may be varied in detail without departing from the principle involved. For example, it is obvious that there may be substituted for the sliding bar *u* and lever *t* the modification shown in Fig. 5 consisting of a ⁸⁰ rocking sector *u'*, link *t'*, and bell-crank lever *t*⁸⁵ in operative connection with the sliding sleeve *t* of the governor, the rocking sector *u'* being provided, as shown, with the lugs *v* *w* in operative proximity to the lug *x*.

Having thus described our invention, we claim—

1. In an engine of the class described, the combination of a lever in operative connection with an exhaust-valve, a spring for holding said valve normally closed, means for actuating said lever to open the exhaust-valve with each alternate revolution of the shaft, engaging lugs in operative connection with the engine-governor and arranged to be actuated thereby, and means upon said lever for engaging one or the other of said lugs when the engine is running at abnormal speed, substantially as described.

2. In an engine of the class described, the combination of a vibratory lever in operative connection with an exhaust-valve, a spring for holding said valve normally closed, means for actuating said lever to open the exhaust-valve with each alternate revolution of the ⁹⁰ shaft, engaging lugs in operative connection with the engine-governor and arranged to be actuated thereby, means upon said lever for engaging one or the other of said lugs when the engine is running at an abnormal rate ⁹⁵ of speed, and means in operative connection with a treadle mechanism for controlling the position of said engaging lugs independently of the normal action of the governor, substantially as described.

3. In an engine of the class described, the combination of a governor, a pivoted lever in operative connection therewith, a slide-bar pivoted to said lever and having engaging lugs thereon, an exhaust-valve, a pivoted lever and spring for holding the same normally closed, means for actuating said lever to open the exhaust-valve with each alternate revolution of the shaft, and a lug upon said lever arranged to engage one or the other of ¹⁰⁰ said first-named lugs when the engine is running above or below its normal rate of speed and to pass between the same when said engine is running at its normal speed, substantially as described.

4. In an engine of the class described, the combination of a governor, a pivoted lever in operative connection therewith, a slide-bar pivoted to said lever and having engaging

lugs thereon, an exhaust-valve, a pivoted lever and spring for holding the same normally closed, means for actuating said lever to open the exhaust-valve with each alternate revolution of the shaft, a lug upon said lever arranged to engage one or the other of said first-named lugs when the engine is running above or below its normal rate of speed and to pass between the same when said engine is running at its normal speed, lever y in operative connection with the lever which is immediately controlled by the governor, and

means, such as a treadle, for actuating the lever y at the will of the operator, substantially as described.

In testimony whereof we have signed this specification, in the presence of two subscribing witnesses, this 23d day of August, 1897.

HUGH PERRONET THOMPSON.
LOUIS MONTÉ.
